UNITED STATES PATENT OFFICE

RALPH E. PAGE, OF BINGHAMTON, NEW YORK, ASSIGNOR TO THE TABULATING MACHINE COMPANY, OF ENDICOTT, NEW YORK, A CORPORATION OF NEW JERSEY

QUICK PAPER INSERTING DEVICE

Application filed September 16, 1926. Serial No. 135,792.

This invention relates to accounting machines and more particularly to a paper inserting device to be used in conjunction therewith.

5 In machines of the above type considerable time is wasted in positioning the paper with regards to the margin desired at the top, whereas in my device this operation is done simultaneously with the paper inserting 10 operation.

An object of my invention is to improve generally an apparatus of this kind.

Another object is to provide economic and efficient means for inserting paper under the 15 platen roll.

Another object is to provide convenient means so that substantially any part of the paper may be brought into relation with the platen roll.

20 A further object is to eliminate the adjusting of the paper after it has been inserted under the platen roll.

A still further object is to provide a storage roll whereby the data printed on a sheet 25 of paper may be wound simultaneously with the printing operation.

Other objects and advantages of my invention will be set forth in the following description and drawings in which:

30 Fig. 1 is a side elevation of my device according to the invention;

Fig. 2 is a detail view of the paper feeding mechanism shown in Fig. 1;

Fig. 3 is a sectional view taken on line 3—35 5 of Fig. 1;

Fig. 4 is a sectional view showing the coil spring and governor for returning the rack to normal position;

Fig. 5 is a sectional view taken on line 40 5—5 of Fig. 1.

Referring more particularly to the drawings, Fig. 1 comprises a frame 1 attached to an accounting machine or the like in the usual manner so that the platen roll will be 45 in position to cooperate with the type.

Mounted in said frame is a platen roll 2, Fig. 3, revolved by means of shaft 3 rotatably supported on frame 1. A dispensing roll 4 is provided for feeding paper 5 onto platen roll 2. Rigidly affixed to dispensing roll 4 at each end is a shaft 6 which revolves in frame 1. At the uppermost end of frame 1 is another roll 7 acting as a storage or receiving roll. Storage roll 7 is revolved by means of shaft 8 and supporting center 8a. 50 A shaft 15 is provided at the left side and has slidably mounted thereon a supporting center 16 which is actuated by spring 17 into engagement with roll 7. By pressing supporting center 16 against coil spring 17 said storage roll 7 may be easily removed. Shaft 8 revolves in frame 1 and boss 9 and has mounted thereon at 10 a friction driving ring (see Figs. 1 and 3) which friction driving ring has affixed thereto a pulley 11. 55 Friction driving ring 10 is comprised of two portions 10a and 10b hinged at 10c closed upon shaft 8 by means of spring 19. Friction driving ring 10 and pulley gear 11 are freely mounted on shaft 8. By means of a nut or washer 12 fastened to the end of shaft 8, pulley 11 is held in position. Fixed onto shaft 3 at 13 is another pulley which upon rotation of platen roll 2 causes pulley 11 to be rotated through the medium of a belt 14. 60 Pulley 13 is larger than pulley 11 in order that the roll 7 shall turn more rapidly than the platen and thus hold the paper tightly wound thereon. As the paper 5 accumulates on the storage roll 7 it is obvious that as the 65 roll becomes larger rotation of same will become slower although belt drive 14 continues to run at the same speed. Friction driving ring 10 will slip upon shaft 8 thereby causing roll 7 to revolve at a much slower speed than that of driving belt 14.

Referring to Figs. 1 and 2, rigidly affixed to disc 21 is a spur gear 20 both being freely supported upon shaft 3. Gear 20 meshes with the teeth 44 of rack 27. Pivoted to disc 70

21 at 22 is an actuating pawl 23 biased by spring 24 to cause engagement of said pawl with ratchet wheel 25. Ratchet wheel 25 is rigidly affixed to star gear 26 which star gear is firmly mounted on shaft 3. When rack 27 is pulled to forward position, pawl 23 actuated by spring 24 cooperates with ratchet wheel 25 and causes rotation of platen roll 2. Rack 27 has fixed thereon extending horizontally on the inside of same a channel bar 10 which holds said rack in place by means of roller bearings 28 which bearings are carried by frame 1 by means of brackets 29. Extending along the top and bottom of rack 27 are 15 teeth 44 meshing with spur gear 20 and pinion gear 30. A groove 31 is provided on the front of rack 27 to cooperate with stop 32. Stop 32 (see Fig. 5) is slidably mounted on rack 27 by means of flanges 33 reaching over 20 the back of the rack. A tooth plate 32a fixed to the stop 32 meshes with the rack teeth 44 to prevent the stop from creeping. By slightly lifting and sliding stop 32 it may be moved along the teeth on the rack to any desired 25 position. After the determined position is reached tooth plate 32a on stop 32 meshes with the teeth 44 on the upper part of rack 27 and same is rigidly held in position by turning of set screw 34 which set screw has a 30 wedge shape projection 35 gripping itself firmly into groove 31 on rack 27. Wedge shape projection 36 on stop 32 upon pulling of rack 27 to forward position engages itself in star gear 26 (see also Fig. 2) thereby allowing the paper inserted on the platen roll to be rotated an equivalent distance to which the stop 32 had been previously set. A handle 37 (Fig. 4) is rigidly affixed to rack 27 at 38 and provides for the pulling of said 40 rack to forward position. As shown at 37a on the rack 27 numerals and graduations may be provided to enable the operator to determine where to set stop 32. When rack 27 is pulled to the forward position pinion 30 45 mounted on shaft 39 causes a tension to be made upon coil spring indicated by dotted lines 42a in drum 42 (see Fig. 3). The coil spring automatically returns rack 27 when released to its normal position. The spring 50 box or drum 42 is mounted on frame 1 by means of a plate 41a and screws 41. A governor indicated by dotted lines 42b may also be provided in drum 42 to prevent shock when said rack 27 is returned to its normal position. 55 The construction and arrangement of the spring and governor are not shown in detail as any conventional construction may be employed. After rack 27 has been returned to its normal position a pin 43 firmly fixed on 60 rack 27 engages with the tail 23a of pawl 23 drawing same out of engagement with the ratchet 25 thereby allowing the carriage to be turned manually in either direction.

65 Having described my invention, what I

claim and desire to secure by Letters Patent is:

1. In a printing mechanism, a platen roll, a notched wheel fixed relative to said roll, a rack and pinion for driving said roll, and a 70 stop having teeth coacting with the teeth on said rack for adjustably mounting the stop on said rack, said stop adapted to enter one of the notches in said wheel to stop the rotation thereof.

75 2. In a printing device, a shaft, a roll carried thereby, a ratchet wheel also carried by said shaft, means comprising a rack and pinion rotatable for one revolution or over by 80 the rack for driving said shaft, a pawl carried by and rotatable with said pinion adapted to engage said ratchet wheel to effect the driving of said shaft in one direction only, and means carried by said rack for disengaging the pawl from the ratchet wheel to permit the roll to be moved in said direction independently of said pawl, pinion, and rack.

85 3. In a printing device, a platen roll, a ratchet wheel and pawl mechanism for driving said roll in one direction only, a manually 90 operated device movable in one direction for actuating said ratchet wheel and pawl mechanism and including gear means having a pinion coaxial with the ratchet wheel, means for automatically returning said device to its 95 initial position, and means rigidly carried by said device for contacting the pawl and thereby disengaging said pawl from said ratchet wheel after said device has returned to initial 100 position to permit one of the elements of said ratchet mechanism to move relative to the other in either rotary direction.

105 4. In a printing mechanism, a platen roll, a ratchet wheel rigid with respect to said roll, a star wheel also rigid with respect to said roll, a pinion, a pawl carried by said pinion adapted to drive said ratchet wheel in one direction only, a rack for driving said pinion, said rack carrying a stop adapted to contact with said star wheel to stop the rotation 110 of said platen roll when the rack is moved in one direction, and a pin carried by said rack adapted to contact said pawl when the rack is moved in the other direction to disengage it from said ratchet wheel.

115 5. In a printing machine, a platen roll, a gear associated therewith, a rack meshing with said gear, a second gear also meshing with said rack, means on said rack adapted to be manually manipulated to move said 120 rack, means for coupling platen roll to said first-named gear to effect rotation of the platen upon movement of the rack in one direction, said second gear adapted to move said rack back to initial position and a governor 125 connected to said second gear for governing the speed at which said rack is returned.

130 6. In a printing mechanism, a platen roll for carrying and feeding a sheet, and means

for line spacing the sheet comprising a notched wheel fixed relative to the platen roll, means for rotating the roll, and a tooth adjustably carried by said means and adapted 5 to mesh with one of the notches in the wheel to stop the feeding of the sheet and aline it in proper spaced position.

7. In a printing mechanism, a platen roll for carrying and feeding a sheet, a notched 10 wheel fixed relative to the roll, rack and pinion means for driving the roll, a tooth carried by said rack and extending substantially parallel to the rack for meshing with one of the notches in the wheel to stop the feeding of the 15 sheet and aline it in proper spaced position.

In testimony whereof I hereto affix my signature.

RALPH E. PAGE.
